UNITED STATES PATENT OFFICE.

CHARLES H. WARNER, OF BELOIT, WISCONSIN.

COMBINED TACHOMETER AND CYCLOMETER.

No. 813,681.

Specification of Letters Patent.

Patented Feb. 27, 1906.

Application filed September 6, 1904. Serial No. 223,342.

To all whom it may concern:

Be it known that I, CHARLES H. WARNER, a citizen of the United States, residing at Beloit, in the county of Rock and State of Wisconsin, have invented a new and useful Combined Tachometer and Cycloometer, of which the following is a specification.

This invention relates to combined tachometers and cycloometers.

10 The object of the invention is to provide a device which is simple and efficient for simultaneously measuring the speed rate and number of rotations of shafts.

15 A further object of the invention is to provide in a single structure or device means whereby the speed of rotation of a shaft, as well as the number of revolutions made thereby within a given time, may be simultaneously measured, recorded, and indicated at a 20 glance.

Other objects of the invention will appear more fully hereinafter.

25 The invention consists substantially in the construction, combination, location, and relative arrangement of parts, all as will be more fully hereinafter set forth, as shown in the accompanying drawings, and finally pointed out in the appended claims.

30 Referring to the accompanying drawings, and to the various views and reference-signs appearing thereon, Figure 1 is a view in top plan of a combined tachometer and cycloometer embodying the principles of my invention. Fig. 2 is a view in side elevation of the 35 same. Fig. 3 is an end view. Fig. 4 is a view in central longitudinal section on the line 4 4, Fig. 1, looking in the direction of the arrows. Fig. 5 is a view in transverse section on the line 5 5, Fig. 4, looking in the direction of the arrows. Fig. 6 is a detail view 40 in section on the line 6 6, Fig. 4, looking in the direction of the arrows. Fig. 7 is a detached detail view of the cycloometer, the supporting-clamp therefor being shown in section. Fig. 8 is a view similar to Fig. 3 with the end cap removed. Fig. 9 is a broken detail view in section, showing a modified form 45 of gearing for actuating the cycloometer and embraced within the spirit and scope of my invention.

The same part is designated by the same reference-sign wherever it occurs throughout the several views.

In Patent No. 745,468, issued December 1,

1903, to A. P. and C. H. Warner, is shown, 55 described, and claimed a magnetic tachometer for measuring and indicating the speed of rotation of shafts, and wherein is employed a magnet and a magnetic mass, one of these parts adapted to be connected to rotate with 60 the shaft the speed of which is to be measured, and a graduated disk is interposed between the magnet and mass and is journaled to freely rotate under the influence of the magnetic field created by the relative rotation of the magnet and magnetic mass, being 65 yieldingly restrained from such free rotation by a spring. The present invention combines with an instrument of this nature a cycloometer, whereby not only the speed of rotation of the shaft may be measured and indicated at a glance, but also and simultaneously therewith the number of rotations made by the shaft in a given time, and the total 70 number of such rotations may also be indicated and recorded.

In the accompanying drawings reference-sign A designates a casing having a hub B, in which is received a bearing-block C, and in which bearing-block is journaled to rotate, 80 preferably on ball-bearings, a sleeve D, to which is connected the instrument-shaft E. The shaft E is designed to be connected in any suitable or convenient manner with a shaft F, the rotations of which are to be measured, indicated, and recorded. As above indicated, any suitable or convenient form of connection between the instrument-shaft E and the shaft F may be employed. I have shown a form of connection which I have 85 found in practice to well answer the purpose, but to which my invention is not to be limited or restricted, wherein the instrument-shaft E is provided with a flexible portion G, which is of the usual form of flexible shafts 90 and which, if desired, may be inclosed in a flexible tubing or covering H. The portion G of the instrument-shaft terminates in a nib J for attachment to the shaft F, as clearly 95 shown in Fig. 2.

100 From the foregoing it will be seen that when shaft F is rotated the rotations thereof are transmitted to the rotating part D of the instrument and which is journaled, as above described, in the bearing-block C. Suitably supported on to rotate with the rotating part D is a circular or ring-shaped magnet K inclosed within casing A, and stationaril

mounted within casing A is a coöperating magnetic mass L. A disk M, journaled to freely rotate within casing A and interposed between the relatively rotating magnet K 5 and magnetic mass L, is provided with an annular flange N, suitably graduated, the graduations thereon being disclosed through an opening in the side of casing A, a stationary pointer O coöperating therewith, as indicated in the drawings. The rotation of disk M may be yieldingly opposed in any convenient manner—as, for instance, by a spring R.

Suitably mounted upon the hub B is a sleeve or drum P, through which the instrument-shaft E extends. This sleeve or drum is formed or provided with a flange S. A casting A' is secured at one end by a bolt B' or otherwise to casing A and at its other end by a bolt C' or otherwise to the flange S. A bracket D' is connected pivotally or otherwise, as indicated at E', to casting A' to afford means for attaching the instrument in convenient position with reference to the shaft the rotations of which are to be measured, recorded, and indicated. I do not desire, however, to be limited in respect of these details of construction for mounting and supporting the instrument, as the same may be altered and varied throughout a wide 30 range without departure from the spirit and scope of my invention.

The casting A' is provided with a split portion forming spring-jaws F' G', in which are formed dovetailed seats H' J' to receive the coöperatingly-shaped shank K' of the casing L' of the cyclometer. This cyclometer may be of the usual or any well-known type and construction. I have found in practice that a cyclometer of the well-known "Veeder" 35 type is well adapted to my purposes and embodies two sets of registering wheels, the members of each set forming with themselves, respectively, registers or recorders for units, tens, hundreds, and the like and actuated the one from the other in the ordinary manner. The units-wheels of both sets may be primarily actuated from the instrument-shaft E in any convenient manner. For instance, and in the form shown in Figs. 4, 6, 40 and 7, the cyclometer is provided with a star-wheel M', with which engages an arm N', mounted upon to rotate with the instrument-shaft E. As shown, this arm forms the end of a spring O', coiled upon a hub P', carried by shaft E and arranged within sleeve or drum P.

In Fig. 9 I have shown another arrangement for operating the cyclometer register-wheels, which arrangement I prefer to employ, and wherein the shaft A' of the instrument is provided with a worm-gear B', with which meshes a worm-gear C', carried upon the shaft of the cyclometer.

The operation of the device will be readily understood from the foregoing description

and is as follows: Rotation being imparted to the instrument-shaft, the speed of such rotations is measured by the tachometer, while the number of revolutions made by such shaft are registered by the cyclometer, the tachometer being operated by the magnetic action of the relatively rotating magnet and magnetic field, which relative rotation is effected by the rotations of the instrument-shaft, while the cyclometer is operated by the arm N' periodically engaging the arms of the star-wheel M', in the one case, or by the intermeshing worm-gears B' C', in the other case, and in either case the rotations being imparted from the instrument-shaft, thereby enabling the speed of rotation of such shaft to be measured and simultaneously therewith the number of such rotations to be recorded and such measurements and registers to be indicated at a glance.

A device embodying my invention, while well adapted for use in measuring, registering, and indicating the rotations of shafts generally, is specially useful in connection with automobiles, enabling the driver or chauffeur to see at a glance not only how fast he is traveling, but also how far he has gone on a trip, and how far he has traveled during the season or within a given space of time.

It is obvious that changes and variations 95 may be readily made in the details of construction and arrangement of the tachometer, as well as of the cyclometer, and still fall within the spirit and scope of my invention, which resides more particularly in the broad 100 combination of these elements and their conjoint and coöperative relation in effecting the objects and purposes had in view.

Having now set forth the object and nature of my invention and a construction embodying the principles thereof, what I claim as new and useful and of my own invention, and desire to secure by Letters Patent, is—

1. The combination with a shaft and means for rotating the same, of a tachometer having a hub, a sleeve connected to said hub, and a cyclometer, and means actuated by the rotations of said shaft for operating said tachometer and cyclometer, the cyclometer-actuating means being inclosed within said sleeve.

2. The combination with a casing and a sleeve or drum carried thereby, a magnetic tachometer arranged within said casing, a cyclometer supported respectively by said casing and sleeve or drum, a shaft extending through said drum or sleeve, and means operated by the rotations of said shaft for actuating both said tachometer and said cyclometer, the cyclometer-operating means being arranged within said sleeve or drum.

3. The combination with a magnetic tachometer having a rotating part, an inclosing casing therefor, a sleeve carried by said casing, a casting connected at one end to said casing and at the other end to said sleeve, a

cyclometer supported by said casting, a shaft extending through said sleeve and connected to the rotating part of said tachometer, connections between said shaft and cyclometer for actuating the latter, said connections in closed within said sleeve and means for rotating said shaft.

In witness whereof I have hereunto set my hand, this 1st day of September, 1904, in the presence of the subscribing witnesses.

CHARLES H. WARNER.
